WOOD HEATER

Nicholas S. Kegelianis, Chicago, Ill., assignor to Automat Corporation, New Athens, Ill., a corporation of Illinois

Filed Sept. 10, 1965, Ser. No. 86,942

Term of patent 3½ years

(Cl. D81—19)

FIG. I.

FIG. 2.

FIG.3.

FIG. 4.

FIG.5.

FIG.6.

FIG. 7.

FIG. 1 is a perspective showing one embodiment of my new design;

FIG. 2 is a plan view of the FIG. 1 heater;

FIG. 3 is a view of the bottom of the heater;

FIG. 4 is a view of the heater from the back;

FIG. 5 is an elevation showing the right side of the heater of FIG. 1;

FIG. 6 is an elevation showing the left side of the FIG. 1 heater; and

FIG. 7 is a perspective showing a modification.

The top, bottom, rear and sides of the FIG. 7 embodiment are the same as those illustrated in FIGS. 2-6.

I claim:

The ornamental design for a wood heater, substantially as shown and described.
